UNITED STATES PATENT OFFICE.

GOTTHARDT KOCH, OF CHICAGO, ILLINOIS.

ENGINE-LOCK.

1,252,417.

Specification of Letters Patent. Patented Sept. 7, 1920.

Application filed May 3, 1919. Serial No. 294,420.

To all whom it may concern:

Be it known that I, GOTTHARDT KOCH, a citizen of Germany, residing at Chicago, in the county of Cook and State of Illinois, have invented certain new and useful Improvements in Engine-Locks, of which the following is a specification.

My invention relates to engines locks and has for its primary object the provision of an improved lock adapted for insertion between the carbureter and intake manifold of an internal combustion engine to control the passage of explosive mixture to the cylinders. A further object is the provision of a key controlled valve operative in normal position to obstruct the passage of explosive mixture from the carbureter to the cylinders of the engine, and which may be moved by the suction of the engine pistons to a position in the intake conduit where it permits the ordinary flow of mixture from the carbureter to the cylinders. A further object is the provision of such a valve in combination with a key controlled lock whereby the valve may be held in normal, obstructing position.

Other objects and advantages of the invention will appear from the following description, taken in conjunction with the accompanying drawings which form a part of this specification and illustrate the preferred embodiment of the invention.

In the drawings:

Figure 1 is a front elevation of the invention showing the same inserted in series in the conduit for explosive mixture for the internal combustion engine, the upper broken portion of the carbureter pipe being shown at the lower extremity of this figure, and the intake manifold of the engine appearing in the upper portion.

Fig. 2 is a vertical, approximately central section of the invention showing the parts in the position they assume when the engine is locked against operation.

Fig. 3 is a similar view showing in full lines the unlocked position of the parts and in dotted lines the position of the valve during the operation of the engine.

Reference numeral 10 indicates the upper extremity of a carbureter chamber through which explosive mixture is drawn to the cylinders of an internal combustion engine, while numeral 11 designates the lower extremity of the intake manifold 12 of the engine. Between carbureter 10 and manifold

11 I insert a substantially cylindrical fitting generally indicated at 13 and comprising a lower tubular portion 14 preferably of the same bore as the carbureter chamber 10 and enlarged in bore in its upper portion as at 15; an inclined shoulder 16 forming the inner surface of fitting 13 between the lower and upper portions 14 and 15.

A yoke 17 spans the opening of fitting 13 at the upper end thereof and carries centrally a vertically apertured boss 18 which forms the bearing for a guide rod 19 on the lower end of which is rigidly carried a valve 21. The valve 21 comprises a piston shaped cup having its cavity uppermost and defined by the side wall 22. Between yoke 17 and valve 21 is compressed a helical spring 23 which exerts downward pressure upon the valve holding it normally in the position shown in Fig. 2, wherein the valve is contained entirely within the lower, smaller bore portion 14 of the fitting and prevents the passage of explosive mixture to the engine cylinders. By means of a head 24 carried on the upper end of guide rod 19, the guide rod and valve are limited on their downward movement.

A lock casing 25 is formed integrally at the right hand side of fitting 13 and is chambered as at 26 to contain any suitable key-operated lock. The details of this lock are not herein shown or described as its particular construction forms no part of the present invention. This lock however is connected to and actuates the crank pin 27 which bears within a vertically attenuated slot 28 formed in the outer end of a valve locking bolt 29, the bolt 29 being horizontally slidable in fitting 13 and being normally pressed to position its inner end 31 above the wall 22 of valve 21 by means of an expansion spring 32 interposed between the outer end of the bolt and the opposite wall of the casing 25. The crank pin 27 is caused to swing about the axis of chamber 26 by means of a key (not shown) but adapted to be inserted in the key hole 33 in the lock above mentioned, said lock being generally indicated as to location by reference numeral 34 in Fig. 1.

The lower surface of bolt 29 is horizontal and, by overlying the upper edge of wall 22 of the valve prevents the valve from rising under the influence of the engine suction. The inner extremity 31 of bolt 29 furthermore is beveled to provide an inwardly and

upwardly exposed cam surface 35, the inner end of the bolt being wedge shaped. The outer side of wall 22 of the valve is recessed opposite bolt 29 to form an upper cam surface 36 steeply pitched from the vertical and a lower cam surface 37 pitched only slightly from the vertical. Upon suitable manipulation of the valve the bolt 29 is adapted to seat within the side recess of wall 22, as shown in full lines in Fig. 3. The lower edge of valve 21 is beveled as at 38, and is adapted to ride upon a cam surface 39 formed on the inner end of a push rod 41 guided in fitting 13 for horizontal movement toward and from the plug. An externally threaded nipple 42 projects to the left hand from fitting 13 at about the level of the valve 21 when the latter is in its normal position. A centrally apertured cap 43 is threaded about this nipple and forms, with the fitting, a bearing for the horizontal movement of the push rod 41. A flange 44 is fixed about push rod 41 just within cap 43, and a spring 45, interposed between flange 44 and casting 13, holds the push rod normally in the retracted position shown in full lines in Figs. 2 and 3. The push rod 41 is held against rotation by means of a fin 46. The upper extremity 30 of the path of movement of valve 21 is illustrated in dotted lines in Fig. 3, and in this position of the valve its wall 22 surrounds a guide wall 47 depending from yoke 17.

In the operation of the invention, and considering the parts to be in the position of Fig. 2 wherein the engine is locked against operation because the presence of the valve 21 in portion 14 of the fitting prevents passage of explosive mixture from the carburetor to the engine cylinders; the operator inserts his key in the key hole 33 and manipulates lock 34 to swing crank pin 27 so as to withdraw the locking bolt 29 from its position above the valve. The action of spring 23 still holds the valve in the position of Fig. 2. The operator now applies his thumb to push rod 41 thrusting it inwardly to bring its cam surface 39 against the bevel 38 of the valve, this inward movement of the thrust rod continuing to the dotted line position of Fig. 3. The valve rides upwardly on the cam surface 39 of the push rod into the full line position of Fig. 3, whereupon the operator releases his hold upon the lock key and permits spring 32 to thrust the locking bolt 29 into the recess 36-37 of the valve wall 22. The relative pitch or slant of surface 36 of the valve and 35 of the locking bolt is such that the bolt retains the valve in this unlocked and slightly elevated position against the downward pressure of spring 23. The operator now removes his thumb from push rod 41 and spring 45 returns this rod to its

normal position. The engine may now be started, inasmuch as the slight divergence from the vertical of surface 37 of the side wall recess in the valve offers no appreciable resistance to movement of the valve by the suction of the engine which draws valve 21 upwardly into the dotted line position of Fig. 3 against the force of spring 23; the surface 37 acting as a cam surface in thrusting the locking bolt 29 slightly outwardly till its inner extremity 31 bears against the vertical side of the valve during the suction induced elevation of the latter. In the upper dotted line position of the valve, as illustrated in Fig. 3, the valve is contained entirely within the upper bore 15 of the fitting 13, this upper bore being of much larger diameter than the valve, while the lower bore 14 of the fitting substantially equals the diameter of the valve. In this upper position of the valve, its bottom is spaced considerably above the upper extremity of the lower bore 14 of the fitting so that explosive mixture may now pass freely from the carburetor 10 to the intake manifold 11. As long as the engine operates the valve is held in this upper position by reason of the suction of the pistons; but when the engine stops, the cessation of suction releases valve 21 to the action of spring 23, so that the valve returns to the full line position of Fig. 2 and the upper edge of wall 22 passes below bolt 29.

When the valve is thus depressed, spring 32 throws bolt 29 above the upper edge of wall 22 of the valve, thus locking the engine against operation by returning the parts to their normal position as shown in Fig. 2. In this return of the valve to normal position, the speed of the valve's movement prevents the locking bolt 29 from seating against surface 36 in the wall of the valve. In the unlocked position of the valve, as illustrated in Fig. 3, the relative slant of surfaces 36 of the valve and 35 of the locking bolt however is such as to hold the valve against the force of spring 23 which tends to further depress the valve.

In order to prevent leakage of air through the key hole 33, chamber 26, and about locking bolt 29 to the interior of fitting 13, the key hole is sealed by means of a cover 48 hinged as at 49 on the casing 25, this cover being, by any suitable means not shown, held against the outer extremity of the lock 34 to prevent passage of air through the key hole 33 while the engine is operating.

While I have shown fitting 13 as a separate element it will be noted that the invention may be incorporated in a suitably formed intake manifold. It is also noted, that when the parts are in the position of Fig. 2, the engine is locked against operation by any unauthorized person; it being

essential that one desiring to run the engine must have a key for the lock 34 before bolt 29 can be withdrawn from its position in the path of movement of the valve.

5 While I have illustrated and described the preferred embodiment of my invention, it will be obvious that one skilled in the art may make modifications thereof without departing from the spirit of the invention. 10 I wish, therefore, not to be restricted to the precise embodiment shown except in so far as the same is limited in the appended claims.

I claim:

15 1. In an internal combustion engine, the combination with an intake manifold fitting, of a device associated therewith and spring pressed to a position wherein it obstructs passage of fluid through the manifold, said 20 device being mounted for suction induced movement to a position wherein it permits passage of fluid, and a key controlled lock-operated bolt mounted for actuation into the path of movement of said device to prevent, at will, the movement of the device 25 from its obstructing position.

2. In an internal combustion engine, the combination with an intake manifold fitting having an upper large bore and a lower 30 small bore, of a valve slidably fitting the smaller bore of the fitting and mounted for suction induced movement therefrom into said large bore, and a key-controlled locking bolt positioned for movement into and out 35 of the path of movement of the valve.

3. In an internal combustion engine, the combination with an intake manifold fitting having an upper large bore and a lower 40 small bore, of a valve slidably fitting the smaller bore of the fitting and mounted for suction induced movement therefrom into said large bore, a key controlled locking bolt positioned for movement into the path 45 of movement of the valve, and a spring positioned to move said valve normally into the small bore of the fitting.

4. In an internal combustion engine, the combination with an intake manifold fitting having juxtaposed aligned small and large 50 bores, of a valve slidably fitting said small bore and mounted in the fitting for movement into said large bore, said movement being in a direction toward the cylinders of the engine, a spring of lesser strength than the engine suction exerting pressure against the valve to move it normally into the smaller bore of the fitting, and key-controlled means for holding the valve in said small bore of the fitting.

60 5. The combination with the intake manifold of an internal combustion engine, said manifold having its axis substantially vertical, of an intake manifold fitting provided with an upper large bore near the engine 65 cylinders and a lower small bore remote

from said cylinders, a valve guided within the fitting for axial movement from one of said bores to the other, and key-operated means for locking the valve within said small bore, said valve being arranged to be 70 opened by engine suction.

6. The combination with the intake manifold of an internal combustion engine, said manifold having its axis substantially vertical, of an intake manifold fitting provided 75 with an upper large bore near the engine cylinders and a lower small bore remote from said cylinders, a valve guided within the fitting for axial movement from one of said bores to the other, and key operated 80 means for locking the plug within the small bore, said means comprising a key operated bolt movable to a position wherein it bears against the upper surface of said valve, said valve being arranged to be opened by engine 85 suction.

7. The combination with the intake manifold of an internal combustion engine, of an intake manifold fitting therefor having a large bore near the cylinders of the engine, 90 and, aligned therewith, a small bore remote from said cylinders, a valve for the small bore guided for movement within the fitting and into the large bore thereof, a spring of lesser strength than the manifold suction 95 positioned to move the valve into the small bore, a locking bolt mounted in the fitting for movement against the valve to arrest travel thereof from the small bore, a second spring positioned to move the bolt normally 100 into said valve arresting position, and key operated means for withdrawing said locking bolt from the latter position.

8. In an internal combustion engine, the combination with the intake manifold there- 105 of, of an intake manifold fitting therefor having a large bore near the cylinders of the engine and a small bore remote from the cylinders, a valve slideable axially of the fitting into the large bore thereof, a valve 110 spring of less strength than the engine suction normally holding the valve within the small bore, a locking bolt slidably mounted in the fitting for movement in a direction angled with respect to the axis of the fitting 115 to prevent movement of said valve from the small bore of the manifold, the outer periphery of said valve being recessed to provide adjacent beveled surfaces, one of said surfaces near the engine cylinders standing at 120 a large angle with respect to such axis, said bolt having its inner edge wedge-shaped for insertion in said peripheral recess and against said bevel surfaces, key controlled means for withdrawing the bolt from the 125 path of movement of the valve, a second spring positioned to move the bolt normally into the path of movement of the valve, and a thrust rod operable from without the manifold and shaped and positioned to 130

strike and move the valve axially of the fitting and in a direction toward the engine cylinders.

9. In an internal combustion engine, the combination with the intake manifold thereof, of an intake manifold fitting therefor having a large bore near the cylinders of the engine and a small bore remote from the cylinders, a valve for the small bore slidable axially of the fitting into the large bore thereof, a valve spring of less strength than the engine suction normally holding the valve within the small bore, a locking bolt slidably mounted in the fitting for movement in a direction angled with respect to the axis of the fitting to prevent movement of said valve from the small bore of the manifold, the outer periphery of said valve being recessed to provide adjacent beveled surfaces, one of said surfaces near the engine cylinders standing at a large angle with respect to the axis of the fitting and the other beveled surface remote from the engine cylinders standing at a slight angle with re-

spect to such axis, said bolt having its inner edge wedge-shaped for insertion in said peripheral recess and against said beveled surfaces, key controlled means for withdrawing the bolt from the path of movement of the valve, a second spring positioned to move the bolt normally into the path of movement of the valve, and a thrust rod operable from without the fitting and shaped and positioned to strike and move the valve axially of the fitting and in a direction toward the engine cylinders, said peripheral recess being positioned at that extremity of the valve nearer the engine cylinders and having that one of its bevels lying nearer said cylinders so related to the adjacent wedge surface of the locking bolt as to prevent relative movement of the valve and locking bolt under the force of the valve spring.

In testimony whereof I have affixed my signature.

GOTTHARDT KOCH.
